M. S. BISHIR

VALVE GRINDING DEVICE

Filed March 22, 1923

UNITED STATES PATENT OFFICE.

MARION SAMUEL BISHIR, OF CANYON, TEXAS.

VALVE-GRINDING DEVICE.

Application filed March 22, 1923. Serial No. 626,889.

To all whom it may concern:

Be it known that I, MARION S. BISHIR, a citizen of the United States, and a resident of Canyon, in the county of Randall and State of Texas, have invented certain new and useful Improvements in Valve-Grinding Devices, of which the following is a specification.

My present invention relates generally to valve grinding devices and more particularly to devices for effectively grinding what are known as overhead valves of the type commonly seated upwardly against the lower seats of their valve cages in use, with which the valves are removable from the cylinder heads, my object being the provision of a device including a holder in which the cage may be effectively clamped in inverted position with the stem of the valve depending and with the valve thus seated downwardly, and resting upon the cage, together with a handle or hand piece capable of movable detachable connection to the valve stem so that by rotation of the handle or hand piece the valve may be ground in much similar manner, and with equal facility and efficiency, to the grinding of a downwardly seating valve in engines having what are known as L-type heads.

A further object is the provision of a device in which the holder for the valve and its cage readily provides for the reception and clamping of cages of various sizes and a still further object is the provision of a device in which the rotatable hand piece may be so engaged with the valve stem that it is capable of actuating and causing rotation of the valve from an angular position with respect to the vertically depending stem.

In the accompanying drawing which illustrates my present invention and forms a part of this specification,

Figure 1 is a perspective view illustrating my invention in its practical application, and

Figure 2 is an enlarged side view of a portion or certain portions, partly in elevation and partly in section.

Referring now to these figures my invention proposes a holder by means of which valve cages such as indicated at 10 may be clamped in inverted position after removal from overhead valve engines employing such valve cages, so that the valve 11, seating upwardly against the seat 12 will,

in this inverted position, rest downwardly on the seat 12 with the stem 13 thereof depending. This holder has an upper head and is preferably formed of a single strip of metal one end of which is bent to inverted U-shape to form the head including side portions 14 and 15 and an upper cross bar 16. The holder also includes a lower upright portion 17 and a lower angular extension 18, the former connecting with the side piece 14 of the head by virtue of an inclined intermediate section 19 and having like the latter apertures 20 for the reception of supporting bolts 21. These bolts come into use through the apertures 20 of the lower upright portion 17 of the holder where the holder is to be attached to a side wall or similar support, and the clamping bolts 21 are used through the apertures of the lower angular extension 18 where the holder is to be secured to a horizontal surface such for instance as a work bench and the like, it being obvious that the lower vertical portion 17 also provides for the ready clamping and support of the holder within a vise or other clamping support of this nature.

The side piece 14 of the head of the holder is provided upon its inner surface with vertically disposed and angularly outstanding clamping wings 22, projecting toward the side piece 15, and the latter has threaded therethrough a clamping bolt or thumb screw 23 which provides for adjustable engagement with the external surface of a valve cage 10 so as to clamp the latter between the inner end of this clamping bolt and the angular wings 22.

My invention also proposes a handle and the like 24 having annular enlargements 25 and 26 at its upper and lower ends and having an axial stem or rod 27 projecting therefrom and provided at its free end with a fixed sleeve 28 adapted to loosely telescope the lower free end of the valve stem 13 and to be movably connected with the said valve stem as by means of a cotter pin 29 extending through diametrical openings in the sleeve and through the elongated or slotted opening 30 adjacent to the free end of the valve stem as usual.

In this way the valve, seating downwardly upon the cage as it will be when clamped in the inverted position in my improved holder, may be rotated by placing the hands upon opposite sides of the handle

or hand piece 24 and twirling the latter between the palms, the lower annular enlargement 16 of the handle permitting downward pressure of the hand at the same

5 time to effectively and snugly hold the valve on its seat. The upper enlargement 25 likewise provides for upward movement of the valve stem when it is desired to lift the valve above its seat either to view its sur-
10 face being ground or that of the valve seat, or for the replenishing of the grinding compound which is used in this operation upon the faces being ground.

It is obvious that by virtue of the loosely 15 telescoping relation of the sleeve 28 of the handle, the latter may be manipulated to effectively rotate or oscillate the valve, while standing at an angle with respect to the valve stems as indicated in the dotted line 20 position of Figure 2 and it is quite obvious from an inspection of either of the figures that it is a simple matter to so clamp the

cage in the holder as to allow the valve 11 to be easily lifted during oscillation and grinding thereof for the purposes before 25 described.

I claim:

In a valve grinding device, a support for a valve cage and its valve including a body formed of a bar having a lower upright 30 portion and an angular extension at the lower end of the upright portion and having an inclined portion at the upper end of the said upright portion and a downwardly opening U-shaped head at the upper end 35 of said inclined portion thus offset by the inclined portion from the lower upright portion, said head having a V-shaped valve cage seat at the inner portion of one side thereof, and a clamping screw working 40 through the opposite side thereof and located at approximately the center of the said seat as described.

MARION SAMUEL BISHIR.
